CLAIM

The ornamental design for a work area screen as shown and described.

DESCRIPTION

FIG. 1 is a top front-right perspective view of a work area screen;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom front-right perspective view thereof.

The broken lines in FIGS. 1-5 and 7-8 immediately adjacent the shaded areas represent the bounds of the claimed design, while all other broken lines illustrate portions of the article that form no part of the claimed design. The work area screen is illustrated with symbolic break lines along its length in those same figures, where the appearance of any portion of the article between those symbolic break lines forms no part of the claimed design.
